UNITED STATES PATENT OFFICE.

SIDNEY COHEN, OF NEW YORK, N. Y.

COMBINATION LOCK.

Application filed May 4, 1925. Serial No. 27,665.

The present invention relates to a combination padlock, particularly of the type in which a plurality of superposed rotatable members are adapted to cooperate with a notched shackle or locking member in a manner to lock it, and which members in one of two predetermined positions are adapted to release the shackle. Inasmuch as the positions are determined by limited movement to the right or left, the lock may 10 be readily manipulated by the sense of touch, and in the dark if necessary.

An object of the invention is to provide a lock of this character, which will be of a very simple construction, and in which the parts are so designed that they are entirely interchangeable, thereby greatly facilitating and economizing the manufacture and assembly of the lock. In particular, it is proposed 20 to provide a plurality of rotatable members which are identical in form, and which may be so arranged within the lock casing as to operate either to the right or left, as desired, or upon either limb of a two-limb shackle, or 25 to the right or left upon a single limb shackle.

A further object is to provide, in one embodiment of the invention, a two-limb shackle, in which the two limbs are symmetrical and have opposed and aligned notches, so 30 that when removed from the lock casing it may be reinserted into operative relation with either limb at either side of the casing. The quantity production of such a shackle 35 may furthermore be carried out with great precision, and with relatively simple and efficient machines.

With the above and other objects in view, embodiments of the invention are shown in 40 the accompanying drawings, and these embodiments will be hereinafter more fully described with reference thereto, and the invention will be finally pointed out in the claims.

In the drawings:

Fig. 1 is a front elevation of a padlock, according to one embodiment of the invention;

Fig. 2 is a vertical sectional view of the same, the rotatable members in Figs. 1 and 2 being in fully locked position;

Fig. 3 is a horizontal sectional view, taken along the line 3—3 of Fig. 1;

Fig. 4 is a horizontal sectional view, taken along the line 4—4 of Fig. 1;

Fig. 5 is a horizontal sectional view similar to Fig. 4, but with the rotatable mem-

bers in unlocked or shackle-releasing position;

Fig. 6 is a perspective view of one of the rotatable members from one side;

Fig. 7 is similar view of the same from 60 the opposed side;

Fig. 8 is a vertical sectional view of a modified form of the invention;

Fig. 9 is a top plan view of the same, the shackle being shown in opened position; 65

Fig. 10 is a vertical sectional view of another modified form of the invention;

Fig. 11 is a horizontal sectional view thereof, taken along the line 11—11 of Fig. 10;

Fig. 12 is a horizontal sectional view of 70 a further modified form of the invention; and

Figs. 13 and 14 are plan views of the two types of rotatable members, adapted to be employed with the form of the invention 75 shown in Fig. 12.

Similar reference characters indicate corresponding parts throughout the several figures of the drawings.

Referring to the drawings, and more particularly to Figs. 1 to 7 thereof, the embodiment of the invention shown therein comprises a casing 10 having a central cylindrical pocket or cavity 11, and at each side there are formed cylindrical bores or passages 12 and 13, opposed to each other and encroaching on the pocket 11. The pocket is adapted to contain the plurality of rotatable rings, presently to be more fully referred to, and which surround the central post 14 of a top or closure member 15, the post being threaded at its lower end, as at 16, and screwed into the base of the casing, which is suitably apertured and threaded for this purpose. The top is furthermore provided 85 with circular openings 17 and 18, which in the fully closed position register with the passages 12 and 13 to receive the limbs of the inverted U-shaped shackle 19, which in such engaged position retains the position of the top. It is obvious that upon removal of the shackle the top may be unscrewed and removed for the purpose of having access to the rings.

The limbs of the shackle are each provided at their inner sides, and at their position normally within the passages 12 and 13, with spaced notches 20 in opposed and aligned relation to each other and to the rings.

The limbs of the shackle are each provided at their inner sides, and at their position normally within the passages 12 and 13, with spaced notches 20 in opposed and aligned relation to each other and to the rings.

The rings 21, as shown in Figs. 6 and 7, are of identical form and correspond in thickness to the distance between the centers of the adjacent notches of the shackle 5 limbs, so that if there are eight notches in each limb, there will be eight rings, the central lateral planes of the rings passing centrally through the notches. The rings are each provided at opposed sides and along 10 a diametric line with projecting studs 22 and 23, which in the engaged position of the ring in the pocket 11 are adapted to respectively engage in a vertical pocket 24 formed interiorly in the rear wall of the 15 pocket and in a vertical opening or slot 25 provided in the front wall of the casing, the pocket and slot being in opposed relation. At one side the ring is provided with a flattened portion 26, parallel with the diametric line upon which the studs 22 and 23 are formed, and which is adapted to abut the solid portions of one shackle limb above and below one of the notches, and permits 20 limited movement of the ring in opposed directions, such movement being further determined by abutment of the stud engaged in the slot 25 against the side walls thereof. The ring is further provided at its other side, in opposed relation to the flattened 25 portion 26, with a recessed formation, including an arcuate cut-out or notch 27, which when brought into registry with the shackle limb in one moved position of the ring permits the shackle to be moved, and 30 adjacent one side of said cut-out there is provided a flange 28 medially disposed with relation to the upper and lower surfaces of the ring, and adapted in the other moved position of the ring to engage in a notch 35 of the shackle limb to retain it. The flange is formed by recessing the upper and lower surfaces of the ring, as at 29, in continuation of the cut-out 27, and in symmetry with the curve of the cut-out. It will be seen 40 from Figs. 3 and 4 that the single type ring may, by inverting it about its two diameters, be arranged to lock on either limb, and, by rotation to the right or left, as desired. As shown in Figs. 1 to 4 the rings 45 are all in their fully locked positions, the combination to open the lock being 1, 2, 3, 2, the first, fourth, fifth and sixth rings being movable to the right, and the second, third, seventh and eighth being movable to the 50 left, to open the lock, Fig. 5 showing the unlocked relation of the rings in which the shackle may be withdrawn. As shown in Fig. 2 the rings are arranged so that the successive rings lock on alternate sides, so 55 as to equalize the strain, but this is not essential, the correspondence between the two limbs permitting any desired arrangement.

In Figs. 8 and 9 I have illustrated a modification, in which one limb of the shackle

is longer than the other, and is provided with a longitudinal slot 30 engaged by a lug 31 provided in the opening 17 of the top, said slot connecting with an annular slot 32 near the lower end of the limb extending 70 partially around it in opposed directions from the slot 30, and provided at one end with a vertical slot 33 extending to the lower end of the limb. The annular slot is in such relation that when the shackle is 75 withdrawn and said slot engaged with the lug 31, the short limb of the shackle is free from the top, and the shackle may therefore be turned in either direction without entirely removing it, as shown in Fig. 9, it 80 being possible, when desired to remove the same, to bring the vertical slot 33 into registry with the stud 31, whereupon the shackle may be removed.

In Figs. 10 and 11 I have illustrated a 85 further modified form, in which the shackle has a slotted limb construction, similar to that shown in Figs. 8 and 9, and in which the other limb 34 is substantially shorter and un-notched. The rings in this form are 90 arranged to lock on only one limb, the single type rings being placed as desired to effect any combination within the permutation limit.

In Figs. 12 to 14 there is illustrated a still 95 further modification, in which the ring has only one lug 35, being reversible about one diameter only, so that in order to provide locking on both limbs, and right and left combinations, it is desirable to have the two 100 types as shown in Figs. 13 and 14, in which the lugs are respectively adjacent the cut-out 27 and the flange 28.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters Patent is:

1. A combination lock of the character described, comprising a shackle having spaced parallel notched limbs, the notches of one limb being in aligned relation with the notches of the other limb, a casing having passages in which to receive the limbs of the shackle, and a plurality of superposed movable members carried by said casing, arranged to engage the notches of the shackle limbs, each member having an elongated portion adapted to permit limited movement of the member in opposed directions relatively to a full portion of one limb, the member having also a shackle releasing portion, which in one position of the member registers with the other limb, so as to allow the shackle to move.

2. A combination lock of the character described, comprising a locking member hav-

- ing spaced notches, a casing having a passage in which to receive said locking member, and a plurality of superposed identical movable members carried by said casing, arranged to engage the notches of said locking member, each member having a releasing portion, which in one position of the member registers with the locking member, so as to allow it to move, means limiting said members to partial movement in two directions, said members adapted in one or the other of said moved positions to register said releasing portions with said locking member, so as to allow it to move, said members adapted in their obverse and reverse positions in said casing, in a given relation to each other and in a given relation of said locking member, to be operable to unlocking positions in respectively opposed directions of movement.
3. A combination lock of the character described, comprising a locking member having spaced notches, a casing having a passage in which to receive said locking member, and a plurality of superposed identical movable members carried by said casing, each having a portion adapted to engage a notch of said locking member, the adjacent members adapted for engagement with adjacent notches of said member, and each having a releasing portion, which in one position of the movable member registers with said locking member, so as to allow it to move, means limiting said members to partial movement in two directions, said members adapted in one or the other of said moved positions to register said releasing portions with said locking member, said members adapted in their obverse and reverse positions in said casing in a given relation to each other and in a given relation of said locking member, to be operable to unlocking position in respectively opposed directions of movement.
4. A combination lock of the character described, comprising a locking member having spaced notches, a casing having a passage in which to receive said locking member, and a plurality of superposed contacting movable members carried by said casing, each having a portion of less thickness than the member and adapted to engage a notch of said locking member, and each having a releasing portion which in one position of the movable member registers with the locking member, so as to allow it to move, means limiting said members to partial movement in two directions, said members adapted in one moved position to register said releasing portions with said locking member.
5. A combination lock of the character described, comprising a locking member having spaced notches, a casing having a passage in which to receive said locking member, and a plurality of superposed contact-
- ing movable members carried by said casing, each having a portion of less thickness than the member adapted to engage a notch of said locking member, and each having a releasing portion which in one position of the movable member registers with the locking member, so as to allow it to move, said first mentioned portion and said releasing portion adapted to respectively limit the movement of the respective members to a partial movement in two directions, said members adapted in one moved position to register said releasing portions with said locking member.
6. A combination lock of the character described, comprising a locking member having spaced notches, a casing having a passage in which to receive said locking member, and a plurality of superposed contacting movable members carried by said casing, each having a portion of less thickness than the member disposed medially between the upper and lower surfaces of the member and adapted to engage a notch of said locking member, and each having a releasing portion which in one position of the movable member registers with the locking member, so as to allow it to move, means limiting said member to partial movement in two directions, said member adapted in one moved position to register said releasing portion with said locking member.
7. A combination lock of the character described, comprising a shackle having spaced parallel notched limbs, a casing having passages in which to receive the limbs of the shackle, and a plurality of identical superposed movable members carried by said casing arranged to engage the notches of the shackle limbs, each member having a releasing portion adapted in one position of the member to register with a shackle limb, so as to allow it to move, means limiting said members to partial movement in two directions, said members adapted in one or the other of said moved positions to register said releasing portions with said shackle limbs, said members adapted by reversal about two diameters at right angles to each other to be operative upon either limb and in either direction of movement.
8. A combination lock of the character described, comprising a locking member having spaced notches, a casing having a passage in which to receive said locking member, and a plurality of superposed rotatable members carried by said casing, arranged to engage the notches of said locking member, each having a releasing portion which in one position of the rotatable member registers with the locking member, so as to allow it to move, and each having diametrically opposed operating means, adapted by reversal of said member about a diameter at right angles to the line of said operating means

to render said member operative by movement in either one of two directions, and means limiting said members to partial rotation in two directions.

9. A combination lock of the character described, comprising a locking member having spaced notches, a casing having a passage in which to receive said locking member, and a plurality of superposed rotatable members carried by said casing, arranged to engage the notches of said locking member, each having a releasing portion which in one position of the rotatable member registers with the locking member, so as to allow it to move, and each having diametrically op-

posed operating means, adapted by reversal of said member about a diameter at right angles to the line of said operating means to render said member operative by movement in either one of two directions, said casing having a concealed slot for receiving the operating means at one side of said members, and a diametrically opposed exposed slot for receiving the operating means at the other side, said members being limited to partial rotation in two directions.

Signed at New York, in the county of New York, and State of New York, this 27th day of April, 1925.

SIDNEY COHEN.
